(57) CLAIM

The ornamental design for an apple-shaped monitor, as shown and described.

DESCRIPTION

FIG. 1 is a perspective view of an apple-shaped monitor showing my new design;

FIG. 2 is a front elevational view thereof in the stored position with the unclaimed circular element attached;

FIG. 3 is a perspective view of a second embodiment thereof; and,

FIG. 4 is a front elevational view thereof in the stored position with the unclaimed circular element attached.

The broken line showings of various elements in FIGS. 1-4 are for illustrative purposes only, disclosing the types of attachments and accessories which can be used with the present design, and form no part of the claimed design. The undisclosed views are not a part of the claimed design.
